B. D. Beecher,

Horse Power.

Patented Dec. 23, 1833.

Benjamin D. Becker of Cheshire Connecticut
Selins Polana

Witnesse whereof I witnesseth and making full
of the same containing a description in the words of the said
Benjamin Becker himself of his improvement to a Hoe Rake.

To all persons to whom these presents shall come, Benjamin
D. Becker of Cheshire New Haven County of the Town of
Cheshire send Greeting. (First known that I Benjamin)
D. Becker have invented contrived, and applied to use a
new and useful improvement in machine for animal
power. Commonly called Hoe power, said improvement and its
manner of building are as follows. 1st This machine is built
by having a plank ten feet long and 10 inches wide and two
thick, placed nine inches below the floor or surface of the
ground and boards nailed across at one end in such a
manner as to form a circle or eight concaved bay three
feet diameter seven sides of which are boarded up ten
inches high and a bay is formed ten inches square to re-
ceive the live shaft. 2nd At the centre is an upright tube
or socket fitted firm to the plank eight inches long three inches
diameter at bottom and two inches at top with a hole through
the centre and one fourth inch diameter bore and smooth
3rd on the outside is a hub well fitted seven inches long the
lower end being connected to a wheel required thirty inches diam-
eter facing inwards and meshing into a pinion of six inches
on a line shaft running horizontally through the ten inch bay.
4th To the end of the shaft is fastened a band wheel turn-
ing six inches diameter from which speed is given to the ma-
chine - 5th In the tube is a wrought iron bolt with a
head at bottom the top being made fast in a cast iron head
through which are two holes at right angles one above the

App. 7883X

other the top one to receive a pin to hold the horse. The other a quoit
or made fast in a hole in the floor twenty two inches diameter
meshing into a pinion made fast to the arms of the thing
which wheel. 6th To the back of the wheel is a wood shaft
one foot long in front of a one thirty inches diameter at one end, and
one at the other the small end attached to the wheel, the other to
the horse, this shaft rolls round on a platform or railing after the
style of which means as follows are given to one of the horses
producing two hundred and fifty turns per minute on the line shaft.

7th By means of this car and railing a complete relief is given
to the horse while the driver cannot feel any undue influence over the
machinery. 8th A similar speed may be given by a wheel attached
to a floor with legs on it, meshing into a pinion the shaft of
which may extend to the center of action, or into the body of a
car, making a travelling machine.

9th The proportions may be varied in any way to suit the fancy
or convenience of the builder or owner.

What a especially claim as my invention and improvement
is the rolling shaft or wheel on a smooth surface and the manner of
conducting and operating the machine.

Reference. - A the revolving shaft to which the wheel B is
firmly fastened. C pinion nine inches made fast to the arms of the
wheel D thirty inches C pinion six inches. E line shaft extending
to the drum outside of the horse track.

Witnesses.
